UNITED STATES PATENT OFFICE.

VINCENT H. FRANCIS, OF DRUMRIGHT, OKLAHOMA, ASSIGNOR TO FRICK-REID SUPPLY COMPANY, OF PITTSBURGH, PENNSYLVANIA, A CORPORATION OF PENNSYLVANIA.

FISHING-TOOL.

1,263,544.

Specification of Letters Patent. Patented Apr. 23, 1918.

Application filed July 16, 1917. Serial No. 180,796.

To all whom it may concern:

Be it known that I, VINCENT H. FRANCIS, a citizen of the United States, and resident of Drumright, in the county of Creek and 5 State of Oklahoma, have invented a new and useful Improvement in Fishing-Tools; and I do hereby declare the following to be a full, clear, and exact description thereof.

My invention relates to fishing-tools for 10 use in connection with oil and other deep wells.

The object of my invention is to provide a simple and compact tool of this character adapted to automatically take hold or grip 15 a portion of a sucker-rod or other device which may have become fastened in the well, and so it may be jarred or worked loose.

To these ends my invention comprises the 20 novel features hereinafter set forth and claimed.

In the accompanying drawing, Figure 1 is a vertical elevation of my improved tool; Fig. 2 is a vertical section showing the tool in the act of engaging the upper end of a 25 sucker-rod; and Fig. 3 is a like view showing the tool after it is engaged by the sucker-rod, and in position for pulling the same upwardly.

In the drawings, the numeral 2 designates 30 the cap or head of the tool, which has the threaded portion 3 engaging the threads 4 on the inner face of the upper end of the shell or casing 5. The casing 5 has the vertical slots 6 formed therein to receive the supporting-arms 7. These arms are secured to the collar 8 by means of screws 9. The collar 8 has the annular groove 10 formed therein and the arms 7 have the projections 11 adapted to enter said groove, said projections being adapted to take the shear of said arms 35 and relieve the strain on the screws 9.

The collar 8 is adapted to move up and down on the support 12 which is screwed at its upper end into the cap 2. The lower end 45 of the support is the head or stop 13 which is engaged by said collar when the arms are lowered as in Fig. 3 and which also regulates the downward movement of said collar 8.

50 As above stated, the supporting-arms 7 fit into the slots 6 and the outer faces of said arms are flush or practically flush with the outer wall of the casing, so that there is no interference in the lowering of the casing 55 into the well.

The lower ends of the supporting arms are provided with the shoulders 14 and below said shoulders the arms are beveled as at 15 to permit the arms to pass readily over the head 16, for instance, at the upper end of 60 the sucker-rod which is to be removed. The outer end of the supporting arms are also beveled as at 17 to conform to the bevel face 18 at the lower end of the shell or casing, and which permits the supporting arms to 65 be moved outwardly as they are engaged by the head 16 of the sucker-rod.

When my improved tool is in use, it is lowered into the well, and when the lower ends of the supporting arms strike the projection 70 or head 16, the arms are forced upwardly with the collar 8 sliding on the support 12 into the position shown in Fig. 2. A further lowering of the tool causes the beveled faces 15 to move over the head 16 forcing 75 the arms outwardly, until the shoulders 14 pass beyond the head 16 whereupon the arms spring inwardly and said shoulders engage the lower face of the head 16, as indicated in Fig. 3. By applying a pull to the tool 80 the sucker-rod may be jarred or loosened and withdrawn from the well. In this way the arms 7 have their shoulders engaging directly under the head 16 of the sucker rod, and there is a direct and positive downward 85 pull on said arms when the force is applied to lift the sucker rod or loosen it from its position in the hole, as distinguished from the ordinary friction hold where teeth are forced into the body of the tool and the 90 hold depends entirely upon friction. Furthermore, all the weight of the spring of sucker rods is carried by the head 13 of the support 12 as the casing 5 carries none of the load. 95

By my invention, I provide a very simple and efficient form of fishing-tool in which the supporting-arms or jaws are held within the walls of the casing so as to leave the outside of the casing smooth and only a small portion at the lower end of the arms projecting into the casing, leaving practically the entire bore open for the introduction of the head or portion of the device in the well which is to be seized by the arms. 100

What I claim is:

1. In a fishing tool, the combination of a suitable casing having a plurality of vertical slots formed therein, a cap in said casing, a supporting member engaging said cap ex- 110

tending down within said casing, a collar movable on said supporting member, supporting arms connected to said collar engaging said slots, and an enlargement on said 5 supporting member engaged by said collar.

2. In a fishing tool, the combination of a suitable casing, having a plurality of vertical slots formed therein, a cap in said casing, a supporting member engaging said 10 cap extending down within said casing, a collar movable on said supporting member, vertically movable supporting arms engag-

ing said slots the lower ends of said arms having tool engaging shoulders, and being beveled at their lower outer edges, and the 15 lower end of said casing having corresponding beveled faces.

In testimony whereof, I the said VINCENT H. FRANCIS, have hereunto set my hand.

VINCENT H. FRANCIS.

Witnesses:

J. H. HUME,
HARRY NEUBEYER.
